UNITED STATES PATENT OFFICE.

PETER T. POTTS, OF CHICAGO, ILLINOIS, ASSIGNOR TO THE VORTEX MFG. CO., OF CHICAGO, ILLINOIS, A CORPORATION OF ILLINOIS.

DESIGN FOR A DISH HOLDER.

Application filed September 6, 1924. Serial No. 10,691. Term of patent 3½ years.

To all whom it may concern:

Be it known that I, PETER T. POTTS, a citizen of the United States, residing at Chicago, Cook County, Illinois, have invented a new, original, and ornamental Design for a Dish Holder, of which the following is the specification, reference being had to the accompanying drawing, forming a part thereof.

I claim:

The ornamental design for a dish holder as shown.

PETER T. POTTS.
